UNITED STATES PATENT OFFICE

JACOB H. WILT, OF MEDINA, OHIO

WELL-DRILLING MACHINE

Application filed August 8, 1928. Serial No. 298,286.

My present invention has reference to a well drilling apparatus, and my primary object is the provision of a portable and collapsible device for this purpose which shall 5 be small and compact but strong and durable; which can be quickly driven to the place of operation, easily and quickly erected for operation and speedy in its drilling action so that the same may be profitably operated. 10 The invention will be fully and comprehensively understood from a consideration of the following detailed description when read in connection with the accompanying drawings which form part of the application, 15 with the understanding, however, that the improvement is capable of extended application and is not confined to the exact showing of the drawings nor to the precise construction described and, therefore, such 20 changes and modifications may be made therefrom as do not affect the spirit of the invention nor exceed the scope thereof as expressed in the appended claims.

In the drawings:

25 Figure 1 is a side elevation showing my improvement set up for operation.

Figure 2 is a similar view showing the device collapsed and folded for transportation.

30 Figure 3 is a detail enlarged sectional view approximately on the line 3—3 of Figure 1.

Figure 4 is an end view of the device in the position described by Figure 1.

35 Figure 5 is a detail elevation to illustrate the manner in which the sand line drum is mounted and movable into or out of engagement with the friction wheel.

Figure 6 is a view substantially similar to Figure 5 but illustrating the manner in which 40 the wire line drum is mounted to be brought into or out of engagement with the friction wheel.

Figure 7 is a perspective view of the brake means on one end of the wire or tool line 45 drum.

Figure 8 is a detail perspective view to illustrate the latch carried by the lower mast section and engageable with the rounds of the upper mast sections for adjustably connecting the mast sections.

Figure 9 is a detail sectional view showing the manner in which the latch engages under a round of the upper mast section.

My improved drilling apparatus is designed to be mounted on the body of a motor truck, as disclosed by the drawings. The truck body is broadly indicated by the numeral 1. On the truck body, at the rear of the driver's seat 1 secure the bed 2 of the improvement. The bed is really in the nature 55 of a metal frame and has its sides, at its ends provided with upstanding posts 3—3 and 4—4, the said posts being braced by angle braces 5—5 and longitudinal braces 6—6. The braced posts 3 have their upper ends 60 connected by a transverse member or head 8. The braced posts 4 have supported and fixed on their upper ends a shaft 7. The shaft 7 is engaged by bearings 9 on the sides 65 10 of the lower mast section. The sides or 70 legs of the lower mast section have their lower or outer ends provided with couplings 11 in which are screwed the ends of a connecting element or pipe 12. The couplings 75 also preferably are formed with heads 13 which afford wide bearing surfaces when the lower mast section is arranged in ground contacting position. The sides or legs of the lower mast section are spaced away from each other a distance greater than the width 80 of the truck body but have their upper portions gradually inclined toward each other, as at 14, and from thence extended in parallelism, as at 15. The parts 15 of the legs are connected together by spaced inner and 85 outer brace plates 16—16 and 17—17, respectively and these brace plates, with the confronting faces of the portions 15 of the lower mast legs provide guides for the legs 18 of the outer or upper mast section. 90

The outer mast section is, of course, slideable in the lower mast section and the outer mast section is provided with spaced rounds 19, respectively. Attached to the lower or inner round 19 of the outer mast section there is a sheave wheel 20, and fixed to the next lower round 19 of the outer mast section there is a cable 21 that is trained around a sheave wheel 22 supported on the inner or lower brace plate 16 of the lower mast section, this 95 100

cable being trained under the sheave wheel 20 and over a second sheave wheel 23 carried by the said plate 16, and this cable may be trained around the drums for either the tool line or the sand line or around a winch 24 which is fixed on one end of the power imparting shaft 25, which will later be described in detail.

What I have termed the lower mast section 10 has its legs provided with truss braces 26, as clearly disclosed by the drawings and the outer or swingable mast section has its legs connected at its outer end by a tubular member 27 on which there are mounted for rotation spaced grooved wheels 28 and 29, respectively. The wheels are held spaced by any desired or preferred means, and the wheel 28 is designed to have trained thereover the sand line 30 while the wheel 29 has trained thereover the wire tool line 31.

Fixed on the outer upper brace plate 17 of the inner or lower mast section there are upstanding plates 32 that have eye ends in which there is either fixed or journaled a rod 25 or shaft 33. On the rod or shaft 33 there are revolvably mounted a pair of stop arms 34. These arms are connected by a rod 35, and to this rod there is secured a light line or wire 36. It is to be noted that the pivot rod 33 passes through the stop arms 34 beyond the center of the said arms, so that the arms are thus weighted. By operating the cable 21 the slideable or outer mast section is elevated or drawn outwardly from the inner mast section 30 and by permitting the stop arms to swing upward of the rounds 19 of the outer mast section and, of course, both of the transverse outer braces 17 of the inner mast section, the outer mast section is sustained at desired 40 elevations with respect to the inner mast section.

Initially, or when the device is not required for use or is being transported, the slideable mast section is moved inwardly through the 45 swingable mast section and both of the mast sections rest on the shaft 7 and the head 8 on the frames of the bed 2. When it is desired to bring the device to operative position I attach a removable sheave block 37 to the connecting element 12 of the lower or swingable mast section and train therethrough a cable 38 which has one of its ends fixed to the bed 2 and its other end wound around either of the drums or the winch 24. A pull upon this 50 cable will swing both of the mast sections on the shaft 7, bringing the mast to a vertical position as disclosed by Figures 1 to 4 of the drawings and in order to rigidly sustain the mast sections in such vertical position, 55 (after the upper or slideable mast section has been adjusted with respect to the lower or swingable mast section) I arrange angle braces 39 between the legs of the swingable mast section and the uprights or posts 3 and 60 secure guy braces 40 between the top of the

slideable mast section and suitable points on the ground. The mast may be set up and securely supported in an easy and expeditious manner and as previously stated, the swingable mast section rests directly on the ground surface or rather the elements 13 contact with such surface. The improvement, of course, includes a power plant which for the sake of economy I make use of the power plant employed for driving a small and well known type of automobile. The drive shaft of this power plant is indicated by the numeral 41. The shaft 41 has freely journaled on one end thereof a worm 42 that is in mesh with a worm wheel 43. The worm 42 has a clutch surface 44 on one end thereof and the drive shaft 41 carries a key that is received in a key-way in a slideable clutch element 45. The clutch element 45 is provided with the usual groove or depression to receive the forked end 85 of a clutch slide or operating member therein. Of course, all of the parts just described are suitably enclosed and as a matter-of-fact, run from a bath of oil and the clutch slide yoke or head is connected to an arm or rod 46 that passes through an opening in the housing 47 for the shaft, clutch elements and wheels. The rod 46 has its outer end connected to an arm which in turn is connected with a link 48, and this link has a connection 90 49 with a transversely arranged shaft 50 which has its ends journaled in suitable bearings and one of its ends formed with an upstanding portion providing a handle 51.

By swinging the handle 51 it will be seen 100 that the clutch 45 may be moved into or out of engagement with the clutch element 49 and also by reference to the drawings it will be seen that the shaft 25 is fixed to the worm wheel 43. The clutch element 45 is brought out of engagement with the clutch element 44 when the motor is running and it is found not desirable to have the shaft 25 rotated or when the planetary gears in the power plant are to be actuated to cause the shaft 105 25 to turn at high or low speeds or in a reverse direction, the change speed gearing being actuated by levers 52, respectively arranged in rear of the bed 2 and, of course, connected by rods 53, respectively, to swingable elements 110 that in turn are connected to the pedals which operate the gears.

On one end of the shaft 25 there is fixed the winch 24 and directly inward of the winch the said shaft 25 has fixed thereon a friction wheel 54.

The second end of the shaft 25 has loosely arranged thereon a crank 55. The hub portion of the crank which is received on the shaft 25 carries a clutch 56. Mounted for movement on splines on the shaft 25 there is a slideable clutch element 57. This element is provided with the usual annular groove 120 that is engaged by the fork 58 and which fork 125

is connected to an operating lever 59 at the rear of the bed.

The friction wheel 54 is centrally formed with a rim enlargement that is designed to be received in a groove 60 or what may be termed a female friction wheel 61 on one end of the drum 62 for the wire tool line. The second end of the drum 62 carries a brake wheel 63 over which is trained a brake band 64. One of the ends of the brake band is connected directly to a shaft 65 and the other end of the brake band is connected to spaced arms 66 that are fixed on the shaft 65. The shaft for the drum and brake wheel is indicated by the numeral 67 and is, of course, journaled in suitable bearings. One end of the shaft 67 is mounted in an eccentric bearing 68 which extends a slight but suitable distance through its bearing box 69, and has attached thereto an arm 70 connected by a link 71 to a crank 72 on the shaft 65. The end of the shaft 65 has fixed thereon an operating lever 73. It will be apparent that by swinging the lever 73 in one direction the friction wheel on the drive will be moved into engagement with the friction wheel 54 and the motor driven shaft 25 which also causes the slackening of the brake band on the brake wheel and when the lever is swung to a second direction the friction wheel on the drum will be brought out of engagement with the friction wheel 54 and the brake band will be tightened on the brake wheel thereby holding the drum from turning.

The drum 74 for the sand line is located above the tool line drum 62, being positioned directly over the friction wheel 54. The shaft 75 for the drum 74 is also mounted in an eccentric bearing 76, the bearing being revoluble in a bearing box 77 therefor, and being provided with an operating lever 78 whereby a friction wheel 79 on the said drum is brought against or sustained away from engagement with the friction wheel 54. It is to be noted that all of the operating levers are arranged at the rear of the device, and, therefore, in close proximity for convenient handling by the operator of the drill.

On the sides or legs of the swingable derrick section there are fixed boxings or bearings 79' for a shaft 80. The shaft 80 extends through one of its bearings 79' and has fixed thereon a block or boxing to whose opposite faces there are secured the inner and thickened ends of leaf springs 81, the outer ends of the said leaf springs being connected by shackles to arms 83 which are secured to the opposite sides of a pitman 84, and the said pitman has its lower end connected to the crank 55.

On the shaft 80 there are fixed the thickened ends of oppositely arched pairs of leaf springs 85—85. These leaf springs are also preferably secured on boxes that are fixed on the shaft 80, and the outer ends of these

leaf springs 85 are connected by a pivot 86 that also affords a shaft for a sheave wheel 87 that is arranged centrally between the springs 85. Journaled on the shaft 80 between the springs 85 there is another sheave wheel 88. The wire tool line that is wound on the drum 62 is trained over the inner sheave wheel 88 and from thence under the outer sheave wheel 87, being directed therefrom over the sheave wheel 28.

The springs just described are important features of the invention. These oppositely directed or curved pairs of springs impart a successive thrust and jerking action to the wire tool line. Thus the rapidly moving tool line is subjected to what may be termed an elastic whip lash action in the up and down movement of the tools, which insures a perfect drilling operation and absorbs all shocks and jars. Also with this arrangement the necessity of a longitudinally movable or telescopic crank for the pitman is entirely obviated.

The parts operated by the engine or power plant, turn, as previously stated, in a bath of oil and are, therefore, constantly lubricated. The reduction gear, that is, the worm and the worm gear, insures a constant and steady action of the crank and pitman. The clutch releases the crank action for elevating the tools while leaving the lines threaded. The transmission serves to increase speed for pulling out tools, etc., while a change of engine speed may be readily and quickly obtained. The improvement, except for the pitman, is constructed wholly of steel and is, of course, light in weight. The improvement is also small and compact so that the mast, when the sections thereof are telescoped and arranged over the truck body will permit of the said truck traveling through any ordinary traffic to haul the improvement in an expeditious manner to the place where the well is to be drilled. The truck, with the improvement supported thereover, is not materially increased in length and may be received in any ordinary garage.

Having described the invention, I claim:

1. In a portable well drilling machine, a mast made up of a pivotally supported section swingable to horizontal and to vertical positions, means for supporting the mast section in either of such positions, and a second sheave carrying section slidably associated with the pivoted section, and means for latching the slidable section adjusted with respect to the pivoted section.

2. In a portable well drilling machine, a mast comprising a pivotally supported section swingable to horizontal and to vertical positions, means supporting the mast section in either of such positions and a second sheave carrying mast section slidably associated with the pivoted mast section, means, comprising a cable trained over pulleys for adjusting

the ⁵ slidable mast section with respect to the pivotally supported mast section, a swingable cable operated latch carried by the pivotally supported mast section, swingable to engage in the ⁵ slidable mast section for holding the mast sections adjusted.

3. In a portable well drilling machine, the combination with a motor actuated pitman, and a mast adjacent to said pitman, of a shaft ¹⁰ journaled in the mast, a grooved wheel fixed on the shaft over which the tool actuating cable is trained, curved springs fixed on the shaft and connected with the pitman, and oppositely curved springs also fixed on the ¹⁵ shaft and a guide wheel journaled through the ends of said last named oppositely curved springs for the tool line.

4. In a well drilling machine, a shaft over ²⁰ which a tool line is trained, yieldable means for imparting an oscillatory movement to the shaft, and spring means carried by the shaft and guide means carried by the spring means for the tool line.

5. In a well drilling machine, the combination ²⁵ of a shaft, a pitman for imparting an oscillatory rotary movement to the shaft, a cantilever spring connection between the shaft and the pitman, said shaft having a tool line trained thereover, laminated springs ³⁰ secured to the shaft and extending in the same direction of and at an opposite angle to the spring connection between the shaft and pitman, and a roller journaled between the last mentioned springs and providing a ³⁵ guide for a tool line.

In testimony whereof I affix my signature.
JACOB H. WILT.
